UNITED STATES PATENT OFFICE.

MARIUS DREYFUS, OF PARIS, FRANCE.

LAMP.

SPECIFICATION forming part of Letters Patent No. 626,990, dated June 13, 1899.

Application filed December 7, 1898. Serial No. 698,545. (No model.)

To all whom it may concern:

Be it known that I, MARIUS DREYFUS, of Paris, France, have invented a new and Improved Lamp, of which the following is a full, 5 clear, and exact description.

This invention relates to improvements in acetylene-gas lamps; and the object is to provide a lamp of this character that shall be simple and strong in construction and having 10 no small tubes or valves to become obstructed or clogged, and, further, to so construct the parts that the water supplied is automatically regulated by the slow and gradual decomposition of the carbid.

15 I will describe a lamp embodying my invention and then point out the novel features in the appended claims.

Reference is to be had to the accompanying drawing, forming a part of this specification, 20 in which the figure is a vertical section of a lamp embodying my invention.

While the drawing shows the lamp arranged as a bicycle or vehicle lamp, it is to be understood that it may be modified for household or other purposes.

25 Referring to the drawing, 1 designates the body of the lamp, which provides a fount for containing the water. Removably connected to the upper end of the body or fount is a cover 2, from which a tube 3 extends down and into the body of the lamp. This tube 3 is adapted to slide its lower end into a jacket 4, and the joint between the tube-section 3 and the jacket 4 is covered by a rubber or 30 similar ring 5 to prevent the entrance of water. At the lower end of the jacket 4 is a diaphragm 6, below which is a chamber 7 for receiving water from the fount, the said water entering through ports 8.

40 Extended upward in the jacket 4 is a perforated wick-carrying tube 9. This wick-carrying tube at its lower end has a screw-thread engagement with an interior threaded opening in a boss 10, formed on the diaphragm 6, and arranged within this tube 9 is a wick 11 45 for carrying water by capillary attraction. The lower end of the tube 9 is designed to be controlled as to the entrance of water by means of a valve, here shown as a plug-valve 50 12, having an exterior screw-thread engaging with an interior screw-thread formed at the lower end of the jacket 4, and on this valve

12 is a lug 13, designed to engage between shoulders 14, formed on the bottom of the body portion 1. To make a tight joint when 55 the valve is closed, a packing 12^a, of rubber or similar material, is placed on the upper end of the valve to engage against the boss 10, which forms the valve-seat.

Removably arranged in the jacket 4 and 60 also extended nearly to the top of the tube 3 is a carbid-holder, here shown as made in three sections 15, 16, and 17, the three sections practically making a single tube or container. The object in making it in sections 65 is for convenience in removing and cleaning the parts when made of metal. It is to be understood, however, that this container may be made of cardboard or similar material, that may be charged with carbid, and when 70 the carbid shall have been destroyed or used up the container may be thrown away, thus obviating the necessity of cleaning. Extended upward in the container and surrounding the tube 9 is a perforated tube 18, which 75 is slightly spaced from the tube 9 and is designed to prevent the carbid from entering through the openings in the tube 9, and it is also designed as a convenient means for lifting the container from the jacket, as will be 80 hereinafter described. This tube 18 passes through a hole in the bottom of the container, and at its lower end it has a flange 18^a, which engages between the bottom of the container and the diaphragm 6, and thus the tube is 85 held in place.

Extended through the top of the cover 2 is a gas-discharge pipe 19, having a burner-tip 20, on which a reflector 21, of any suitable material, may be placed. As here shown, the 90 tube 19 has a portion extended upward, and then it is turned at right angles to the body of the lamp, and through this right-angled portion is an opening 22 and a sleeve 22^a, through which a securing-rod 23 is designed 95 to pass. The lower end of this rod 23 is screw-threaded and adapted to engage in a screw-threaded socket 24, formed in the lamp-body, and the upper end is provided with a hook 25. This rod 23 not only serves to hold 100 the cover 2 and jacket 4 from rotating relatively to the lamp-body, but by means of its hook end the carbid-holder may be lifted from the jacket, as the said hook end is designed

to engage in an opening 26, formed near the upper end of the tube 18.

In operation a supply of water is to be placed in the body or fount of the lamp, and then the jacket containing the carbid-holder, with the carbid therein, is to be placed in position, as indicated in the drawing. When in position, the lug 13 will engage between the shoulders 14. When it is desired to generate gas for lighting purposes, the rod 23 is to be removed, and then the cover, the jacket, and the carbid-holder are to be rotated relatively to the body portion of the lamp in such a direction as to unseat the valve 12 from its engagement with the boss 10. Then the water in the chamber 7 will be absorbed by the wicking 11 and carried upward by capillary attraction and gradually distributed to the carbid, and the gas generated thereby will discharge through the burner 20. Of course when the lamp is in its burning position the rod 23 is to be placed to lock the parts, as indicated. When it is desired to extinguish the light, the rod 23 is to be again removed and the parts rotated in the opposite direction to that above mentioned, so that the valve will shut off the entrance of water to the wicking 11.

Having thus described my invention, I claim as new and desire to secure by Letters Patent—

1. An acetylene-gas lamp, comprising a body portion forming a water-fount, a cover for the body portion, a jacket carried by said cover and extended into the body portion, a valve in the lower portion of said jacket adapted to be opened or closed by a rotary movement of the jacket relatively to the body portion, a carbide-holder removably placed in the jacket, a perforated tube extended upward in said carbide-holder, a perforated tube attached to the jacket and extended upward in said first-named perforated tube, and a burner-tip extended through the cover, substantially as specified.

2. An acetylene-gas lamp, comprising a body portion which forms a water-fount, a cover for said body portion, a jacket carried by said cover and extended into the body portion, the said jacket having a diaphragm near its lower end and a water-chamber below said diaphragm, a perforated tube extended from said diaphragm upward in the jacket and adapted to receive a wicking or similar material, a valve for controlling the entrance of water from the chamber to said wicking or similar material, the said valve being oper-

ated by a rotary motion of the jacket relatively to the body portion, a carbide-container removably arranged in the jacket, a perforated tube extended upward in said container and surrounding the first-named tube, and a burner-tip extended through the cover, substantially as specified.

3. An acetylene-gas lamp, comprising a body portion forming a water-fount, a cover therefor, a jacket carried by the cover and consisting of two separable sections extended into the body portion, a diaphragm arranged near the lower end of said jacket, a tube extended through said diaphragm and upward in the jacket, the said tube being perforated and adapted to receive a wicking, a valve having a screw-thread engagement in the bottom wall of the jacket and adapted to control the supply of water to the wicking, a lug extended downward from said valve and adapted for engagement between shoulders formed in the bottom of the lamp-body, a carbide-container removably placed in the jacket, a perforated tube in said container and surrounding the first-named tube, a gas-discharge tube extended through the cover, and means having connection with said gas-discharge tube, for locking the same in position, substantially as specified.

4. An acetylene-gas lamp, comprising a body portion forming a fount for water, a cover therefor, a jacket carried by said cover and extended into the body portion, a diaphragm near the lower end of such jacket, a perforated tube extended through said diaphragm and upward in the jacket a valve operated by rotary motion of the jacket for controlling the entrance of water to said tube, a carbide-container consisting of separable sections and removably arranged in the jacket, and a gas-discharge tube extended through the cover, substantially as specified.

5. An acetylene-gas lamp, comprising a body portion forming a water-fount, a cover therefor, a jacket supported by said cover and extended into the body portion, a perforated tube extended upward in such jacket and adapted to receive a wicking or similar material, a valve for controlling the supply of water to said tube, a carbide-container removably arranged in the jacket and surrounding the perforated tube, and a gas-discharge tube, substantially as specified.
